F. J. ANDERSON

HINGE

Filed March 12, 1925

INVENTOR.

Pred J. Anderson

BY

Thomas Donnelly
ATTORNEY.

UNITED STATES PATENT OFFICE.

FRED J. ANDERSON, OF DETROIT, MICHIGAN.

HINGE.

Application filed March 12, 1925. Serial No. 14,860.

To all whom it may concern:

Be it known that I, FRED J. ANDERSON, a citizen of the United States, residing at Detroit, in the county of Wayne and State of Michigan, have invented a new and useful Improvement in a Hinge, of which the following is a specification.

My invention relates to a new and useful improvement in a hinge, and has for its object, the provision of a hinge which is normally spring held in closing position, and so arranged and constructed as to exert a closing force upon the door, to which attached, which is constant at all times, irrespective as to whether the door is closed, partly opened, or completely opened.

Another object of the invention is the provision in a hinge, adapted for mounting upon a door, having resilient means for normally moving said hinge to closing position, said resilient means being so mounted as to provide a varying proportion between its compression and its torque, so as to exert a closing pressure constant at all times.

Another object of the invention is the provision of a hinge of this class which will be simple in structure, economical of manufacture, and highly efficient in use.

Other objects will appear hereinafter.

The invention consists in the combinations and arrangements of parts hereinafter described and claimed.

The invention will be best understood from a reference to the accompanying drawings which form a part of this specification and in which,

Fig. 1 is a rear elevational view of the invention,

Fig. 2 is a sectional view taken substantially on line 2—2 of Fig. 1,

Fig. 3 is an elevational view showing the hinge in open position.

As shown in the drawings, the hinge comprises a pair of co-operating leaves 7 and 8, one of which is adapted for mounting upon a stationary supporting surface, and the other of which is adapted for being secured to the door, or other swinging member, with which used. The leaf 7 is provided with a pair of knuckles 9 and 10 which are adapted for positioning between the knuckles 11 and 12 formed on the leaf 8. Projected through the knuckles mentioned

is a shaft 13, provided with nuts 14 and 15 at opposite ends, so as to secure the parts in co-operative position. Positioned upon the shaft 13 in embracing relation is a spiral spring 16, one end 17 of which is angularly turned and engaged in a recess formed in the knuckle 9. Positioned rotatably upon the shaft 13 is a collar 18 projecting outwardly from which is a sleeve 19, which is provided, at opposite sides, with spirally arranged grooves 20 and 21. Projected through the shaft 13 is a pin 22, the ends of which project beyond the periphery of the shaft 13 and engage in the grooves 20 and 21. The opposite end 23 of the spring 16 is angularly turned and engages in a pocket formed in the collar 18. The knuckle 11 is provided with a set screw 24 which may be threaded into engagement with the shaft 13, so as to maintain the knuckle 11 in fixed relation to the shaft 13. The leaf 8 is secured to the supporting surface and consequently, in operation, remains stationary. When the door, which is secured to the leaf 7, is opened, the knuckle 9 is caused to rotate upon the shaft 13. This rotating of the knuckle 9 causes a winding of the spring 16, to produce a greater torque, so that the tension, resulting from the wound arrangement of the spring, is increased. As the leaf 7 is swung on the shaft 13 in response to the opening of the door, the increased tension, on account of the winding of the spring 16, will cause the collar 18 to begin to rotate. As the collar 18 rotates, the end 23 of the spring will move into closer relation to the end of the spring 17 on account of the engagement of the projecting ends of the pin in the slots 20 and 21. This approach of the ends of the spring toward each other causes a compression of the spring, but in approaching, the tension of the spring 16 resulting from the increased winding, is released. The inclination of the grooves 20 and 21 is determined by the increase in tension resulting from the increase in winding of the spring 16, this tension being dependent upon the size of the wires, or the material from which the wires of the spring 16 are made. The inclination of the slots is such that the unwinding at the end 23 will be constant with the winding at the end 17, so that the

2
torque or pressure resulting from the winding of the spring 16 always remains constant. When the door is moved to opened position, the collar 18 is moved into the 5 position shown in Fig. 3.

The torque of the spring 13 may be adjusted by rotating the shaft 13 to the desired position and then tightening the set screw 24, inasmuch as the shaft 13, in rotating, carries with it the lower end 23 of the 10 spring 16.

With a hinge constructed in this manner, there is provided a device whereby the closing pressure exerted on the leaf 7 remains 15 constant at all stages of movement of the leaf 7, rotatably on the shaft 13, relatively to the leaf 8. It will be noted that the angle of the slots determines the proportionate change of compression and torque. When 20 the collar 18 is moved to the position shown in Fig. 3, the compression of the spring will have a tendency to assist in moving the leaf 7 to closing position. Consequently, if the inclination of the slots 21 and 20 is such as 25 to permit an effective result from the compression, the end 23 of the spring will, in opening the door, rotate slightly farther than the end 17. This adjustment of the movements, however, does not affect the 30 principle but is to be determined solely with the particular hinge in which the invention is used. The object of the invention is to provide a hinge in which the closing torque is 35 always constant, no matter whether this torque results from a twisting of the spring or a compression of the spring.

It is believed obvious that many minor modifications of the present invention may be made, such as, threading the shaft 13, 40 and threading the interior of the sleeve 19. However, such minor modifications and changes are intended in the present invention and are desired to be brought within the scope of the appended claims.

45 Having thus described my invention, what I claim as new and desire to secure by Letters Patent is:

1. A hinge of the class described, comprising a pair of relatively movable leaves, 50 one being adapted for mounting upon a stationary supporting member, and the other, adapted for mounting upon a swingable member; a pivot member for permitting the relative swinging of the leaves; and resilient means mounted on said pivotal member for normally moving said leaves into closing relative position, the closing strain produced by said resilient means being constant at all positions of relative movement of said 55 leaves.

2. A hinge of the class described comprising a pair of leaves, one of said leaves being adapted for mounting on a stationary support, and the other being adapted for mounting on a swingable member; a pivot mem- 60

ber for said leaves; a spring mounted on said pivot member in embracing relation, one end of said spring being connected to said leaf mounted on said swingable member and movable in unison with said leaf; a 70 collar mounted on said pivot member, the opposite end of said spring being connected to said collar and movable in unison therewith; a sleeve fixedly connected to said collar and embracing said pivot member, said sleeve having spirally arranged slots formed therein; a pin projected through said pivot member, diametrically thereof, and engaging at its opposite ends in said slots, said spring being adapted for unwinding at one end, upon being wound at the opposite end. 75

3. A hinge of the class described comprising a pair of leaves, one of said leaves being adapted for mounting on a stationary support, and the other being adapted for mounting on a swingable member; a pivot member for said leaves; a spring mounted on said pivot member in embracing relation, one end of said spring being connected to said leaf, 80 mounted on said swingable member and movable in unison with said leaf; a collar mounted on said pivot member, the opposite end of said spring being connected to said collar and movable in unison therewith; a sleeve fixably connected to said collar and embracing said pivot member, said sleeve having spirally arranged slots formed therein; a pin projected through said pivot member, diametrically thereof, and engaging at its opposite ends in said slots, said spring 85 being adapted for unwinding at one end upon being wound at the opposite end; and means for fixing said pivot member against rotation. 90

4. A hinge of the class described, comprising a pair of leaves, one of said leaves being adapted for mounting on a stationary supporting member and the other being adapted for mounting on a door; a pivot member for said leaves; a spring normally under tension for retaining said door in closed position, one end of said spring being attached to one of said leaves and rotatable therewith, the other end being adapted for spiral movement on said pivot member, upon relative movement of said leaves, for maintaining a constant tension on said spring irrespective as to the relative position of said leaves. 100

5. A hinge of the class described, comprising a pair of leaves, one of said leaves being adapted for mounting on a stationary supporting member, and the other being adapted for mounting on a door; a pivot member for said leaves; a collar on said pivot member, adapted for longitudinal movement on said pivot member; means for effecting a rotation of said collar upon longitudinal movement on said pivot member; a spring normally under tension for retaining 110

said door in closed position, one end of said spring being attached to one of said leaves and rotatable therewith, and the other end being attached to said collar and movable therewith, said other end being adapted for spiral movement on said pivot member, upon relative movement of said leaves, for main-

taining a constant tension on said spring irrespective as to the relative position of said leaves.

10

In testimony whereof, I have signed the foregoing specification.

FRED J. ANDERSON.
